UNITED STATES PATENT OFFICE.

OLIVER E. TEALL, OF SAUGERTIES, NEW YORK, ASSIGNOR TO THE TISSUE COMPANY, OF SAUGERTIES, NEW YORK, A CORPORATION OF NEW YORK.

DESIGN FOR A CONTAINER FOR PAPER NAPKINS.

56,730.

Specification for Design.

Patented Dec. 7, 1920.

Application filed August 5, 1918. Serial No. 248,487. Term of patent 7 years.

To all whom it may concern:

Be it known that I, OLIVER E. TEALL, a citizen of the United States, residing at the city of Saugerties, in the county of Ulster, State of New York, have invented a new, original, and ornamental Design for a Container for Paper Napkins, of which the following is a specification, reference being had to the accompanying drawing, forming part thereof.

The container is preferably of glass and is adapted to contain previously folded and interleaved paper napkins.

In the drawing the figure is a view in perspective showing my invention.

I claim:—

The ornamental design for a container for paper napkins, as shown.

OLIVER E. TEALL.
